Primary Examiner — Mojtaba Tehrani*(74) Attorney, Agent, or Firm* — Warn Partners, P.C.(57) **CLAIM**

The ornamental design for a caliper cover as shown and described.

DESCRIPTION

FIG. 1 is a perspective view of a caliper cover, showing a new design;

FIG. 2 is a front view;

FIG. 3 is a top view;

FIG. 4 is a left side view;

FIG. 5 is a right side view;

FIG. 6 is a rear view; and,

FIG. 7 is a bottom view of the fourth embodiment.

Broken lines in the drawings depict unclaimed portions of the caliper cover and form no part of the claimed design.
